UNITED STATES PATENT OFFICE

LOUIS N. D. WILLIAMS, OF OGONTZ, PENNSYLVANIA, ASSIGNOR TO SCOTT & WILLIAMS, INCORPORATED, OF NEW YORK, N. Y., A CORPORATION OF MASSACHUSETTS

MECHANISM FOR TRANSFERRING KNITTED WEBS

Application filed December 14, 1922, Serial No. 606,787. Renewed September 27, 1927.

This invention relates to knitting and more particularly to the transfer of knitted webs.

An object of the invention is to provide improvements in that type of stitch transferring device shown and described in my application for United States Letters Patent filed February 23, 1923, bearing Serial No. 620,587; and which consists, briefly, of mechanism designed to apply a transfer ring to the needles of a circular knitting machine for the purpose of transferring the stitches from said needles to the points of the ring, so that the knitted web may be removed with said ring; or for the purpose of transferring stitches from the points of the ring to the needles. In the operation of transferring knitted web, as conducted with the mechanism shown in the said application, the ring is placed in a ring carrier and the latter automatically swung to position to cooperatively register the points of the transfer ring with the needles. After the desired transfer of stitches is effected the ring carrier is swung away, and the ring left in position upon the needle bed to be removed by hand.

The improvements contemplated by the present invention are, first; to construct the ring carrier and its operating mechanism so that after the stitches have been properly transferred from the needles to the points of the ring, or vice versa, the point ring is removed from the needle cylinder automatically by its carrier. Second; to provide improved mechanism for moving the yarn guide ring of the knitting machine out of the way of the point ring to enable application of the latter to the needles, and third; to provide a construction that will permit my invention to be used in connection with a knitting machine equipped with a ribbing or welting dial.

These objects I accomplish in the manner hereinafter set forth, reference being had to the accompanying drawings, in which I illustrate, for example, mechanism employed when transferring stitches from the needles of a knitting machine to the points of a transfer ring.

In the drawings, Fig. I is a view in elevation of part of a circular knitting machine showing my present invention. In this view, the point ring is shown in section and as supported by its carrier in idle position. 55

Fig. II is a similar view showing the carrier swung to register the points of the ring with the needles.

Fig. III is a similar view showing the point ring lowered to impale the stitches upon the needles. 60

Fig. IV is a plan view of the knitting machine and the parts of my invention showing the latter in the positions assumed in Fig. II.

Fig. V is a view of the machine in end elevation, and partly in section, illustrating my improved yarn guide ring operating mechanism and the embodiment of my invention in a knitting machine equipped with a dial. 65

Fig. VI is a view similar to Fig. V but illustrating another means for moving the yarn guide ring to one side; and, 70

Fig. VII is a view in section—taken on the line VII—VII of Fig. V—showing a 75 locking disc for the transfer mechanism of a rib machine.

Proceeding to a detailed description of the mechanism and referring to Figs. I—IV inclusive, the needle cylinder 1 is rotatably mounted on the bed plate 2, to which the bracket 3 is secured, the latter affording support for a post 4 which provides bearing for a horizontal rock shaft 5. At the outer end of this shaft 5 there is mounted in fixed engagement a spur pinion 6 which intermeshes with a gear sector 7 having an angularly directed arm 8, the sector being loosely mounted upon a horizontal shaft 9. An anti-friction roller 10 is carried by the arm 8 and rides in a peripheral cam slot 11 formed in a cam drum 12 adapted to rotate about a vertical axis under intermittent actuation. This cam drum 12 is provided with two other cam slots 14 and 15, for a purpose 95 to be presently noted.

Fixedly mounted upon the rock shaft 5 is a bell crank, the arm 16 of which serves to support the point ring carrier, which comprises a circular holder 17 with which the 100

arm is formed, and a sleeve 18, slidably and rotatively held within the holder 17 and in turn adapted to slidably receive the point ring indicated comprehensively at 19. Ordinarily the sleeve 18 is locked against rotation by means of a lug 20 secured to the holder 17, and against sliding movement by means of a spring pin 21 mounted upon the said holder 17. Thus proper initial alignment of the elements is insured.

The point ring 19 is applied to the carrier when the latter is in the retracted position shown in Fig. I. When the knitting operation is completed, rotation of the cam drum 12 is begun, the action of which is to swing the sector 7 with consequent partial rotation of the pinion 6 and turning of the shaft 5. The point ring carrier is thereby swung to the position shown in Fig. II with its points 22 registering with the needles of the cylinder 1. The bell crank of which the arm 16 constitutes a part includes an arm 23 which carries a laterally projecting pin 24. When in this position the pin 24 is located directly above the upper end of a rod 25 the lower end of which is operated by the slot 15 in the cam cylinder 12. This rod 25 is raised by the action of the cam slot 15 to the position shown in Fig. III so that its upper end 30 bears firmly against the under face of the pin 24 thereby serving to lock the point ring carrier securely in position against backward yielding. The carrier is limited in its downward movement by engagement of a laterally protruding finger 26—carried by the holder 17—with the upper end of a post 27 which projects upwardly from the bed plate 2 of the machine.

Rotatably mounted in the arm 16 is a shaft 28 having one of a pair of arms 29 secured to each end forming a yoke which embraces the holder 17. One arm 29 is extended as at 30 to carry a pin 31. Projecting inwardly from the yoke terminals 29 are pins 32 which pass through slots 33 in the sides of the holder 17 and enter an annular groove 34 in the outer face of the sleeve 18.

With the point ring carrier in the position shown in Fig. II the pin 31 on the extension 30 is lodged in a laterally recessed head 35 formed on the upper end of a rod 36, the lower end of which is operated by the slot 14 in the cam drum 12. Under the action of this cam slot 14 the rod 36 is raised to the position shown in Fig. III, rocking the shaft 28 and lowering the yoke arms 29, which act through the pins 32, to carry the sleeve 18 down, thereby releasing said sleeve 18 from the retaining action of the lug 20 and spring pin 21. As the point ring 19 is carried by the sleeve 18 it also moves downwardly, and its points 22 are caused to impale the stitches on the needles of the cylinder 1 as shown in Fig. III.

The needle cylinder 1 is then rotated for the purpose of retracting the needles so as to leave the stitches upon the points 22 of the point ring 19, this ring rotating with the needle cylinder 1 and the sleeve 18 rotating with the point ring 19. When this period of rotation is completed and the stitches are transferred, the rod 36 is depressed by action of the cam slot 14, raising the sleeve 18 without disturbing the holder 17, and consequently lifting the point ring 19 from the needle bed of the machine. The rod 25 is then depressed by the cam slot 15, to release the pin 24 and permit the cam drum 12 to act through the medium of cam slot 11 and gear sector 7 with correlated parts to swing the point ring 19 back to the position shown in Fig. I, carrying upon its points the stitches of the knitted web for the purpose of subsequent handling. The transfer or point ring 19 is held against accidental dislodgment from the sleeve 18 by means of a spring catch 37 pivotally mounted upon said sleeve and entering a notch 38 in the point ring.

Forming part of the transfer or point ring 19 is an annular stripping element 39 having radial fingers which extend outward between the points 22. The stripping element 39 is carried by rods 40 which slide in the point ring 19 and are connected at their inner ends to an annular member 41 engaged by a thrust rod 42 which has bearing in the sleeve 18 and is connected at its outer end to an arm 43 pivotally mounted between spaced extensions of the bell crank arm 16. The thrust rod 42 is maintained firmly in contact with the member 41 by means of a spring pressed finger 44, which is pivotally mounted upon the arm 16 of the carrier bell crank, and it engages a notch 45 in the fulcrum boss of the arm 43. The parts remain in this position during movement of the carrier from the position of Fig. I to that shown in Fig. II; but when the rock shaft 28 is turned to move the sleeve 18 and point ring 19 to the position shown in Fig. III driving the points 22 downward beyond the fingers of the stripping element 39 and impaling the stitches on the needles, the spring finger 44 is released from the notch 45 in the boss of arm 43 by means of an actuating lug 46 on the lever extension 30, as shown in Fig. III. The arm 43, under the influence of a spring located therebeneath is forced upwardly, withdrawing the thrust rod 42 from contact with the annular member 41; consequently, when the point ring 19 is raised from the needle bed, the element 39 will not be projecting and there will be no possibility of the stitches becoming dislodged from the points 22 of the ring 19. The friction between the rods 40 connecting the stripping element 39 and the annular member 41, and the channels in which said rods

slide is such as to retain the stripping element 39 in any position to which it is moved. After the point ring 19 with the web upon it has been removed—by releasing the catch 37—from the carrier sleeve 18 preparatory to the application of another ring thereto, the spring finger 44 is reset so that it enters the notch 45 in the fulcrum boss of arm 43. This is conveniently effected by means of a handle 47 integrally formed with the arm 43. It will thus be seen that the operation of the machine is entirely automatic, the empty point ring 19 being applied to the carrier sleeve 18 while the latter is in the position shown in Fig. I and later removed therefrom when said ring is returned to such position; the stitches previously on the needles of the machine being then impaled upon the points 22 of said ring.

Before the point ring 19 can be applied to the needles it is necessary that the yarn guide ring indicated at 48 be moved out of the way; and one means which may be used for doing this is disclosed in Fig. V; wherein I show the yarn guide ring 48 as secured to a shaft 49 journaled in bearings at the ends of posts 50 projecting upwardly from the bed plate 2 of the machine. To one end of the shaft 49 is secured a spur pinion 51 which intermeshes with a gear sector 52 loosely mounted upon a stud 53 projecting from a suitably disposed extension of the bracket 3. The gear sector 52 is formed with an arm 54 which carries an anti-friction roller 55 operating in a cam slot 56 in a supplementary cam drum 57.

The action of the cam slot 56 upon the roller 55 is such as to swing the yarn guide ring 48 upwardly and out of the way. Supplementary cam drum 57 is preferably driven from the cam drum 12 by means of intermeshing spur gears 58.

In Fig. VI, I have illustrated another means for moving the yarn guide ring 48 out of the way. In this instance the ring 48 is secured to a hollow stem 59 vertically movable upon a post 60 projecting upwardly from the bed plate 2 of the machine. This construction requires the use of the gears 51 and 52 and cooperating parts described in the last paragraph in connection with Fig. V. Movement of the cam 57—as before described—rocks the shaft 49, and in this form said shaft is provided with a supplementary spur pinion 61 intermeshing with a rack 62 formed on the hollow stem 59. As the pinion 61 is rotated it raises the stem 59 consequently lifting the yarn guide ring 48 vertically out of the way.

In Fig. V, I have illustrated a construction that may be used when my invention is to be applied to a knitting machine having a dial. In this view a ribbing dial 63 is shown as driven by a central shaft 64 which receives its motion from a transverse

shaft 65 through the medium of bevel gears 66. The shaft 65 is—in turn—driven by a vertical shaft 67 through the medium of bevel gears 68, and said shaft 67 is driven, in any suitable manner, from the main driving shaft of the knitting machine.

A supporting frame 69 for the ribbing dial 63 and the shafts 64 and 65 is mounted upon the upper face of the yarn guide ring 48; and when said yarn guide ring is swung out of the way, the ribbing dial 63 with its driving mechanism accordingly moves with it. As it is necessary, when the ribbing dial 63 is returned to place, that its parts be in absolutely the same positions they occupied before said dial was swung upwardly, I provide for this purpose a locking mechanism which comprises a spring pressed lever 70 fulcrumed upon the supporting frame 69 and normally bearing at its outer end against the upper end of the vertical shaft 67. As soon as the yarn guide ring 48 and ribbing dial 63 begin to move out of the way, the lever 70 is pressed by its spring and enters the notch 71 of a disc 72 which is fixed on the shaft 65, thereby locking the latter against rotation and preventing movement of any of the parts of the ribbing dial 63. When the ribbing dial 63 is returned to the normal position shown in Fig. V, the outer end of the lever 70, at the terminus of the swing, strikes against the upper end of the vertical shaft 67 and is lifted out of the notch 71, thereby releasing the parts while the gears 68 are brought into mesh.

The same construction is applicable to a welting dial, and either dial may be mounted upon the yarn guide ring 48, as shown in Fig. VI. In this case it would not be necessary to provide locking means for the driving gear inasmuch as the gearing could be so mounted as to ride with the dial without any disengagement of elements.

Having thus described my invention, I claim:

1. The combination with the needle cylinder of a knitting machine of a transfer ring, a movable carrier for the transfer ring, and automatic mechanism for moving the transfer ring carrier from an inactive position into operative relation with the needle cylinder, for manipulating said transfer ring in the carrier incidental to transfer of fabric, and for subsequently returning the carrier to the inactive position to remove the point ring and transferred fabric from the needle cylinder.

2. The combination with the needle cylinder of a knitting machine of a transfer ring, a movable carrier for supporting the transfer ring with capacity for axial shifting, and automatic mechanism for moving the transfer ring carrier from an inactive position into operative relation with the needle cylinder, for shifting the transfer ring in its car-

rier incidental to transfer of fabric, and for subsequently returning the carrier to inactive position to remove said transfer ring and transferred fabric from the needle cylinder.

3. The combination with the needle cylinder of a knitting machine of a point ring, a movable carrier for the latter embodying a circular holder, and a sleeve for accommodating the point ring rotatable in the holder for movement with the needle cylinder during transfer.

4. The combination with a needle cylinder of a knitting machine of a point ring, a movable carrier for the latter embodying a circular holder, and a sleeve for accommodating the point ring, said sleeve being capable of longitudinal movement in the holder to advance the points of the ring into engagement with the knitting needles.

5. The combination with the needle cylinder of a knitting machine of a point ring, a movable carrier for the latter embodying a circular holder, and a sleeve for accommodating the point ring, said sleeve being capable of longitudinal movement to advance the points of the ring into engagement with the needles, and of rotation for movement with the needle cylinder during transfer.

6. The combination with the needle cylinder of a knitting machine of a point ring, a movable carrier for the latter embodying a circular holder, a sleeve for accommodating the point ring, said sleeve being longitudinally movable in the holder to advance the points of the ring into engagement with the needles of the machine, and means for normally preventing movement of said sleeve in respect to said holder.

7. The combination with the needle cylinder of a knitting machine of a point ring, a movable carrier for the latter embodying a circular holder, a sleeve for accommodating the point ring movable within said holder, means for moving the carrier to bring the points of the ring into registry with the needles of the machine, and means for moving the sleeve aforesaid independently of the holder to advance the points of the transfer ring into engagement with the needles of the knitting machine.

8. The combination with the needle cylinder of a knitting machine of a point ring, a movable carrier therefor, means for automatically moving said carrier to apply the points of said ring to the needles, a yarn guide ring cooperating with the needles during the knitting operation, and means for automatically moving said yarn guide ring out of such cooperating position before the movement of the point ring carrier, said latter means comprising a rock shaft, a pinion on said shaft, a gear sector intermeshing with said pinion, means for moving the sector, and means interposed between

said yarn guide ring and said rock shaft whereby rotation of said rock shaft causes movement of said yarn guide ring.

9. The combination with the needle cylinder of a knitting machine of a point ring, a movable carrier therefor, means for automatically moving said carrier to apply the points of said ring to the needles, a yarn guide ring cooperating with the needles during the knitting operation, and means for automatically moving said yarn guide ring out of such cooperating position before the movement of the point ring carrier, said latter means comprising a shaft on which said yarn guide ring is mounted, a pinion on said shaft, a gear sector intermeshing with said pinion, and means for moving the sector.

10. The combination with the needle cylinder of a knitting machine of a point ring, a movable carrier therefor, means for automatically moving said carrier to apply the points of said ring to the needles, a yarn guide ring cooperating with the needles during the knitting operation, and means for automatically moving said yarn guide ring out of such cooperating position before the movement of the point ring carrier, said latter means comprising a shaft on which said yarn guide ring is mounted, a pinion on said shaft, a gear sector intermeshing with said pinion, a cam controlling the sector, and means for moving said cam.

11. The combination with the needle cylinder of a knitting machine of a transfer ring, a carrier for the transfer ring, a yarn guide ring and a dial cooperating with the needle cylinder during the knitting operation, and automatic mechanism including cam drum means to move the transfer ring carrier, the yarn guide ring and the dial aforesaid, alternately into operative relation with the needle cylinder.

12. The combination with the needle cylinder of a knitting machine of a point ring, a movable carrier therefor, means for automatically moving said carrier to apply the points of said ring to the needles, a dial cooperating with the needle cylinder during the knitting operation, and means for automatically moving said dial out of said cooperative position before the movement of the point ring carrier, said latter means comprising a rock shaft, a pinion on said shaft, a gear sector intermeshing with said pinion, means for moving the gear sector, and means whereby rotation of said rock shaft causes movement of said dial.

13. The combination with the needle cylinder of a knitting machine of a point ring, a movable carrier therefor, means for automatically moving said carrier to apply the points of said ring to the needles, a dial cooperating with the needle cylinder during the knitting operation, and means for auto-

- matically moving said dial out of said cooperative position before the movement of the point ring carrier, said latter means comprising a shaft on which said dial is mounted, a pinion on said shaft, a gear sector intermeshing with said pinion, and means for moving the sector. 14. The combination with the needle cylinder of a knitting machine of a point ring, a movable carrier therefor, means for automatically moving said carrier to apply the points of said ring to the needles, a dial cooperating with the needle cylinder during the knitting operation, and means for automatically moving said dial out of such cooperative position before the movement of the point ring carrier, said latter means comprising a shaft on which said dial is mounted, a pinion on said shaft, a gear intermeshing with said pinion, a cam controlling the gear, and means for moving said cam. 15. The combination with the needle cylinder of a knitting machine of a point ring, a movable carrier therefor, means for automatically moving said carrier to apply the points of said ring to the needles, a yarn guide ring and associated dial cooperating with the needle cylinder during the knitting operation, driving mechanism for said dial including separable elements, means for automatically moving said yarn guide ring and dial out of cooperative relation with the needle cylinder before the movement of the point ring carrier, and means for automatically locking those elements of the driving mechanism carried with said yarn guide ring and dial during the time it is out of such cooperative relation. 16. The combination with the needle cylinder of a knitting machine of a point ring, a movable carrier therefor, means for automatically moving said carrier to apply the points of said ring to the needles, a dial cooperating with the needle cylinder during the knitting operation, driving mechanism for said dial including separable intermeshing gears, means for automatically moving said dial out of cooperative relation with the needle cylinder before the movement of the point ring carrier, and means for automatically locking the driving mechanism of said dial during the time it is out of such cooperative relation, said locking means comprising a notched disc movable with the dial, and a member adapted to engage with said disk and prevent rotation thereof while the gears are out of mesh. 17. The combination with the needle cylinder of a knitting machine of a point ring, a movable carrier therefor, means for automatically moving said carrier to apply the points of said ring to the needles, a yarn guide ring and a dial cooperating with the needle cylinder during the knitting opera-
- tion, and means for automatically moving the yarn guide ring and said dial out of cooperative position before the movement of the point ring carrier, said latter means comprising a rock shaft, a pinion on said shaft, a gear sector intermeshing with said pinion, means for moving the gear sector, and means whereby rotation of said rock shaft causes movement of said yarn guide ring and dial. 18. The combination with the needle cylinder of a knitting machine of a point ring, a movable carrier therefor, means for automatically moving said carrier to apply the points of said ring to the needles, a yarn guide ring and a dial cooperating with the needle cylinder during the knitting operation, and means for automatically moving said yarn guide ring and dial out of cooperative position before the movement of the point ring carrier, said latter means comprising a shaft on which said yarn guide ring and dial are mounted, a pinion on said shaft, a gear sector intermeshing with said pinion, and means for moving the sector. 19. The combination with the needle cylinder of a knitting machine of a point ring, a movable carrier therefor, means for automatically moving said carrier to apply the points of said ring to the needles, a yarn guide ring and a dial cooperating with the needle cylinder during the knitting operation, and means for automatically moving said yarn guide ring and dial out of cooperative position before the movement of the point ring carrier, said latter means comprising a shaft on which said yarn guide ring and dial are mounted, a pinion on said shaft, a gear intermeshing with said pinion, a cam controlling the gear, and means for moving said cam. 20. The combination with the needle cylinder of a knitting machine of a point ring, a carrier therefor embodying a circular holder permitting movement of said point ring with the needle cylinder during transfer, and mechanism controlled by the cam drum adapted to automatically actuate the carrier. 21. The combination with the needle cylinder of a knitting machine of a point ring, a carrier therefor controlled by a cam drum, automatically-actuated means for moving such carrier to apply the points of said ring to the needles, a yarn guide co-operating with the needles during the knitting operation, and automatically actuated means controlled by the cam drum aforesaid functional to move the yarn guide out of such cooperation in advance of movement of the point ring carrier. 22. The combination with the needle cylinder of a knitting machine of a transfer ring, a carrier for the transfer ring controlled by a cam drum, a yarn guide ring and

5 a dial cooperating with the needle cylinder during the knitting operation, and automatically-actuated mechanism controlled by the cam drum aforesaid governing movement of the transfer carrier and said yarn guide ring and dial so that one is substituted for another in operative relation with respect to the needle cylinder.

10 23. The combination with the needle cylinder of a knitting machine of a point ring, a movable carrier therefor automatically-actuated controlled by a cam drum, means for moving said carrier to apply the points of said ring to the needles, a dial cooperating with the needle cylinder during the knitting operation, and automatically-actuated means controlled by the cam drum aforesaid governing movement of said dial out of cooperative position before movement of the point ring carrier.

15 24. The combination with the needle cylinder of a knitting machine of a point ring, a movable carrier therefor controlled by a cam drum, automatically-actuated means controlled by said cam for moving said carrier to apply the points of said ring to the needles, a yarn guide ring and a dial cooperating with the needle cylinder during the knitting operation, driving mechanism for 20 said dial, and automatically-activated means including the cam drum aforesaid controlling movement of the yarn guide ring and dial out of cooperative relation with the needle cylinder before movement of the point ring 25 carrier.

30 25. The combination with the needle cylinder of a knitting machine of a point ring, a movable carrier therefor controlled by a cam drum, automatically-operated means for moving said carrier to apply the points of said ring to the needles, a yarn guide ring and a dial cooperating with the needle cylinder during the knitting operation, driving mechanism for the dial, automatically-activated means including the cam drum aforesaid controlling movement of the yarn guide ring and dial out of cooperative relation with the needle cylinder before movement of the point ring carrier, and locking 35 means effective to prevent rotation of the dial during the last mentioned movement.

35 26. The combination with the needle cylinder of a knitting machine of a point ring, a movable carrier therefor controlled by a cam drum, automatically-operated means for moving said carrier to apply the points of said ring to the needles, a yarn guide ring and a dial cooperating with the needle cylinder during the knitting operation, and automatically-activated means including the cam drum aforesaid controlling simultaneous movement of the yarn guide ring and dial out of cooperative position before movement of the point ring carrier.

40 27. The combination with the needle cyl-

inder of a knitting machine of a transfer ring, a yarn guide ring co-operating with the needle cylinder during the knitting operation, and automatic mechanism including cam drum means to move the transfer ring carrier and yarn guide ring alternately into operative relation with the needle cylinder.

70 28. The combination with the needle cylinder of a knitting machine, and auxiliary devices proximate the top thereof which normally co-operate with said needles, of a transfer ring, a carrier for the transfer ring, and mechanism including the cam drum means for automatically moving the auxiliary devices out of the co-operative position aforesaid and applying the transfer ring to the needles.

75 29. The combination with the needle cylinder of a knitting machine including auxiliary devices used during normal knitting of a transfer ring, a carrier for the transfer ring, a yarn guide ring co-operating with the needle cylinder during the knitting operation; and mechanism including the cam drum means for automatically moving the transfer carrier, the yarn guide ring, and other auxiliary devices aforesaid, from the region of the needle ends to permit placement of the transfer ring thereover.

80 30. The combination with the needle cylinder of a knitting machine of a point ring, and a movable carrier controlled by the cam drum, said point ring being capable of rotation in the carrier during transfer.

85 31. The combination with the needle cylinder of a knitting machine of a point ring, and a movable carrier under control of the cam drum comprising a circular holder, said point ring being capable of rotation in the carrier with the needle cylinder during transfer.

90 32. The combination with the needle cylinder of a knitting machine of a point ring, a movable carrier for the latter, said point ring being capable of longitudinal movement with the knitting needles, and automatic mechanism for moving the carrier from an inactive position into operative relation with the needle cylinder.

95 33. The combination with the needle cylinder of a knitting machine of a point ring, a movable carrier for the latter, said point ring being capable of longitudinal movement to advance its points into engagement with the needles and of rotation with the needle cylinder during transfer.

100 34. The combination with the needle cylinder of a knitting machine of a point ring, a movable carrier for the latter, said point ring being capable of longitudinal movement in the carrier to advance its points into engagement with the knitting needles, automatic mechanism for moving the carrier from an inactive position into operative rela-

tion with the needle cylinder, and means normally preventing movement of the point ring with respect to said carrier.

In testimony whereof, I have hereunto signed my name at Philadelphia, Pennsylvania, this 12th day of December, 1922.

LOUIS N. D. WILLIAMS.
